UNITED STATES PATENT OFFICE

ALBERT P. J. VOIGT, OF GALVESTON, TEXAS

MUFFLER

Application filed January 7, 1929. Serial No. 380,809.

My invention relates to a muffler for internal combustion engines and it is preferably of the type in which a certain amount of fluid is contained in order to extinguish any sparks which may be emitted by the exhaust.

It is one of the objects of my invention to provide a sleeve which is entirely closed except for a single outlet.

Another object of my invention is to surround the exhaust pipe entering the muffler with a plurality of layers of foraminated material in order that a tortuous passage may be presented for the gases in passing from the inlet to the outlet.

Still another object of my invention is to present a fluid surface to the gases as they are discharged from the exhaust pipe, so that any sparks will be extinguished and any large particles must be broken up by contact with the foraminated material before they are permitted to escape from the muffler.

Other and further objects of my invention will be readily apparent to those skilled in the art to which my invention appertains when the following description is considered in connection with the accompanying drawings wherein:—

Fig. 1 is a cross section on the mid-line of a muffler constructed in accordance with my improved idea.

Fig. 2 is a section taken on the line 2—2 of Fig. 1, and shows the arrangement of the foraminated material and the exhaust pipe in their relation to the outlet.

By having reference to Fig. 1, I have indicated the exhaust pipe at 10 shown as passing through an opening 11 in the sleeve or housing 12, which housing forms the principal body of the muffler. It will be noted that the pipe 10 extends the entire length of the housing 12 and abuts at 13 against the end 14 of said housing. The end 14 thus serves to completely close the end of the exhaust pipe.

A plurality of openings 16 have been shown in the lower side of the exhaust pipe so that gases passing from the engine, as indicated by the arrows, will be discharged downwardly from the exhaust pipe.

My improved muffler is constructed with the closed housing 12 in order that it may

contain a substantial amount of fluid, such as water 17. In this manner the gases being discharged from the opening 16 come directly in contact with the water 17 and any sparks, such as heated particles of carbon discharged from the engine, are quickly extinguished. I have shown two discs 20 mounted eccentrically upon the exhaust pipe 10 and adjacent each end of the housing 12. The housing 12 has been shown made as integral but obviously the end 15 is made removable in order that the exhaust pipe and other internal structures of the muffler may be inserted. The end plates or discs 20 may be welded or otherwise affixed to the exhaust pipe 11 and are formed to serve as supporting members for a baffle composed of a plurality of coils or layers of foraminated material. This material is preferably a fine mesh wire 21 and may be of copper, iron or, if desired, from any noncorrosive material. This wire may be attached to the disc in any desired manner just so that it will not become loosened by vibration or in the use of the muffler.

By having reference to Fig. 2 it will be noted that the exhaust pipe has been placed adjacent the top of the housing 12, leaving considerable space therebelow. In this manner as the exhaust gases pass from the opening 16 they will agitate the fluid 17 so as to cool the wire mesh and absolutely assure that any sparks carried by the gases will be extinguished.

I have shown an outlet 25 as mounted centrally on the upper side of the housing 12. This outlet comprises a dome 26 and discharge pipe 27. I have shown these as placed on the upper side of the muffler housing 12 in order that heavy particles of carbon will not be discharged and also in order that the muffler may contain a substantial amount of fluid.

It seems obvious that in the operation of the device the gases will be well dispersed by the time that they reach the discharge pipe 27 as they are broken up in passing through the several openings 16, whereupon they are compelled to contact the fluid 17 and then subsequently pass through the several coils

or layers of wire mesh so that they are completely cooled and the possibility of discharging any sparks or heated particles is absolutely obviated.

Any suitable means may be provided to replenish the supply of fluid in the muffler, such as a plugged opening in the housing 12, or the cap of the dome 26 may be made removable. This is an obvious expedient and further showing or description of it is not believed necessary.

I have disclosed herein an embodiment of my present improvement which I believe to be entirely satisfactory and practical for the purpose in view. Nevertheless, it is to be understood that the several essential parts of the device might be constructed in various other alternative forms and it is accordingly to be understood that in the future development of the device I reserve the privilege of resorting to all such legitimate changes therein as may be fairly embodied within the spirit and scope of the invention as claimed.

Having thus described my invention, what I desire to secure by Letters Patent is:

1. A muffler for the exhaust of internal combustion engines comprising an exhaust pipe, a housing surrounding said pipe and serving to close the end thereof, an outlet from said housing, and a baffle in said housing and supported by said pipe, including a pair of end plates, a plurality of cylinders of mesh wire carried by said plates and surrounding said pipe, a plurality of openings in said pipe on the lower side thereof, said housing being adapted to be partially filled with liquid whereby sparks may be extinguished.

2. A muffler for internal combustion engines comprising an exhaust pipe, openings therein, a plurality of cylinders of wire mesh surrounding said pipe, discs attached to said pipe and supporting said coils, a housing about said cylinders and adapted to contain a fluid.

3. A device of the character described comprising a housing adapted to contain fluid, an exhaust pipe passing into one end thereof, a plurality of layers of mesh wire surrounding said pipe and within said housing whereby exhaust gases from said pipe are compelled to pass thru said wire, discs on said pipe to support said layers of wire, and an outlet from said housing.

4. In a muffler, a housing, an inlet, an outlet, and means disposed in the path of the gases to cause dispersion thereof before said outlet is reached, said means including a plurality of layers of fabricated wire mesh and discs to support said layers in concentric relation, said inlet discharging in a direction opposed to that of said outlet.

5. In a muffler, a housing, a discharge pipe longitudinally of said housing and having downwardly directed openings therein, said

housing being adapted to contain water to a level spaced slightly below said openings, an outlet above said pipe, a plurality of spaced layers of foraminated material surrounding said pipe in said housing, and means connected with said layers of material and with said pipe so that said material is supported in spaced relation to said pipe.

6. In a muffler, a housing, a discharge pipe longitudinally of said housing and having downwardly directed openings therein, said housing being adapted to contain water to a level spaced slightly below said openings, an outlet above said pipe, discs mounted on said pipe and a tubular section of foraminated material connected with said discs and surrounding said pipe.

In testimony whereof I hereunto affix my signature this 31st day of December, A. D. 1928.

ALBERT P. J. VOIGT.
